UNITED STATES PATENT OFFICE

2,528,771

SECTIONAL CASING FOR FLUID HEATERS

Bernard E. Mustee, Cleveland, Ohio, assignor to
Emil L. Mustee, Cleveland, Ohio

Application June 14, 1944, Serial No. 540,172

2 Claims. (Cl. 220—4)

1

My invention relates to heat interchangers in general, and fluid heaters in particular.

An object of my invention is to provide an insulated fluid heater having removable sides.

Another object of my invention is the provision of an insulated fluid heater having rigid rib members and removable side panels as side members with protecting triple gas seal joints between the panels and ribs and with overlapping gas seal joints between the side members and end members.

Another object of my invention is the provision of an insulated fluid heater simply constructed to provide for an easily accessible interior and economy of construction by the provision of removably mounted snap-in side panels.

Other objects and a fuller understanding of my invention may be had by referring to the following description and claims, taken in conjunction with the accompanying drawing, in which:

Figure 1 is a perspective view of my fluid heater housing as seen from the rib side having a lighter door therein;

Figure 2 is a top view of my fluid heater housing showing the gas exhaust and coil outlet openings;

Figure 3 is a longitudinal sectional view taken along the line 3—3 of Figure 2, and showing the arrangement of heating unit, and coil in relation to my housing unit;

Figure 4 is a cross-sectional view taken along the line 4—4 of Figure 3 to show the interlocking seal between the side members of my housing unit;

Figure 5 is a longitudinal cross-sectional view showing the construction of the lighter door and spring, the side coil port, and the arrangement of outlet ports at the top;

Figure 6 is a perspective view of my fluid heater housing as seen from a panel side thus affording a comparison between panel width and the rib width of Figure 1; and

Figure 7 is a cross-sectional view taken along the line 7—7 of Figure 5, showing the construction of the lighter door and inlet port, respectively, on the rib members.

With reference to the figures of the drawing, I illustrate a type of fluid heater housing 10 which conforms to my invention enclosing a heating unit 27 and a fluid coil 26, having removably attached side panels 11, rib members 12, top end member 13, and bottom end member 14.

As best seen in Figures 3 and 5, the top end member 13 is a dish-shaped rigid member, preferably stamped or cast, and having an exhaust port 15 for burned gases, and a coil outlet opening 16 through which the fluid carrying coil 26

2

may pass. An extreme lip 31 of the top part 13 is preferably formed into a short length of circular perpendicular wall.

The bottom end member 14 is best shown in Figure 3 in a cross-sectional view. It is noted from the Figure 3 that the bottom end member 14 is also a rigid member, preferably stamped or cast, and having one hole for a fuel supply line to pass therethrough. As shown in the drawings, 10 the bottom part 14 is a dish-shaped member with edges formed of a large fillet having a short end lip 32 of parallel circular form. Located circumferentially about the bottom part 14 on the inner side of the sloping or filleted portion thereof, are 15 a plurality of rest members 30 extending inwardly far enough to form rest ledges for the side panels 11.

The two rib members 12 are of rigid construction and are illustrated in the drawing as being 20 secured to the top member 13 and to the bottom member 14 in any suitable manner such as by screws 17. The ribs 12 may be of any suitable width, but are preferably kept relatively narrow to provide for accessibility of the coil 26 and 25 heating unit 27. Because the ribs 12 are secured to the end members 13 and 14, a rigid serviceable frame-work for the completed heater housing is obtained.

An opening 33 is provided in one of the ribs 12 30 to permit insertion of a lighter flame. A door 18 is provided to close the opening 33 as illustrated in Figure 5, and in cross-section in Figure 7. The door 18 is preferably made with a heel part 19 extending past the pivot point of the door. The 35 door is engaged by a spring member 20, shown in Figure 5, which will hold the door in an open or closed position as is desired. An opening 21 is provided in the other of the ribs 12 to permit entry of the fluid coil 26. The ribs 12 are preferably 40 of a channel construction to permit reduction of cost and decrease in weight as well as providing a space for insulation. Insulation material is preferably held within the rib space by a cap 34.

Side panels 11 may be constructed of thin 45 sheet metal or other suitable resilient material and comprise an inner part 22, and an outer part 23 bound together at the sides thereof by lips 24 and enclose a space therebetween as shown in Figures 4 and 7 of the drawing. The parts 22 50 and 23 are rolled or formed into a semi-circular shape as illustrated in the drawing. The lips 24 of the panel 11 are constructed in a Z form to fit the sides of the ribs 12. The space enclosed by the sides 22 and 23 of the panels 11 may be filled 55 with an insulation material 35 and the ends of

the panel closed by a crescent member 25 to render the panels 11 resistant to the passage of heat therethrough.

To enclose the coil 26 and the burner 27, and to prevent loss of heat energy by convection and conduction, the side panels 11 are used to fill the openings between the ribs 12. Because the side panels 11 are constructed of a resilient material in a semi-circular form with edges adapted to engage the ribs 12, the panels are insertable within in the opening between the ribs 12 by constraining the panel 11 to a semi-circular form of a smaller radius than its natural form. After insertion, the panel is allowed to spring back or snap in and close the opening with the edges of the panel engaging the rib members 12.

In order to insert the panel 11 in place after constraining, the panel is inserted upwardly inside the parallel lip 31 of the top part 13 far enough that the bottom of the panel 11 will clear the lip part 32 of the bottom part 14. The bottom part of the panel is then moved inwardly towards the burner 27 until the outer part 23 of the panel 11 is inside the radius of the lip 32 of the bottom part 14. The entire panel is then moved downwardly until it rests upon the rest member 30 within the bottom part 14. The panel is next relieved of the compressing force which constrains the lip parts 24 of the panel 11 towards one another in order that the lips 24 might spring back and engage the edge of the rib members 12. As is best shown in Figure 4, the lip part 24 contacts the rib member 12 in three places, thereby producing a relatively gas-tight joint between the panel 11 and the rib member 12. Also, because the panels 11 are longer than the distance between the top parts 13 and the bottom part 14, an overlapping is provided which serves as a very efficient gas seal.

My heater housing may be used to enclose any suitable heat exchanger mechanism such as the fluid carrying coil 26 and the heating element 27. The burner or heating element 27 is located at the lower end of the heater housing, as illustrated in Figure 5, and is supplied by means of a fuel pipe 28 passing through the opening of the bottom part 14. Gases resulting from combustion of fuel are carried from the face of the burner or heating element 27 upward through the heater housing 10 and out through the exhaust port 15. The fluid coil 26 is connected to an outside main through the openings 21 and 16 whereby cold water may enter at the bottom of the heater housing, be warmed by the rising gases of combustion, and exit through the top of the heater housing.

When my heater housing is constructed as described, the outside will present a smooth symmetrical appearance, and the inside will be smooth and even all around with no projecting surfaces to produce local heating of the side wall.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A housing unit for a heater, comprising oppositely facing similarly dimensioned end parts, rigid rib means rigidly connecting corresponding peripheral portions of said end parts to space

and support the end parts from one another, said end parts and rib means comprising a frame for said housing unit, and defining at least an opening into said housing, at least a resilient panel member to close the opening, said at least a panel member and said rib means comprising an annular wall enclosing the housing unit between said end parts, said rib means having first and second annularly spaced radially extending vertical walls and first and second annularly spaced laterally extending vertical walls, said first radial and first lateral vertical walls meeting in acute angular relationship and defining a first panel retaining notch, said second radial and second lateral vertical walls meeting in acute angular relationship and defining a second panel retaining notch, said resilient panel having first and second lateral edges with means thereon complementarily fitting in gas-seal engagement with said first and second panel retaining notches respectively and with the inner edge of the first and second radially extending vertical walls, said resilient panel being wider than the distance between said first and second panel retaining notches when the panel is in an inoperative position, whereby said first and second lateral edges of the panel will be tightly pressed into engagement with said first and second retaining notches when the panel is in an operative position.

2. A housing unit for a heater, comprising a first vessel-shaped end part having an edge lip with an internal annular wall surface, a second vessel-shaped end part having an edge lip with an internal annular wall surface, said first and second vessel-shaped end parts being oppositely facing and similarly dimensioned, rigid rib means rigidly connecting corresponding peripheral portions of said end parts to space and support the end parts from one another, said end parts and rib means comprising a frame for said housing unit and defining at least an opening into said housing, said edge lip of the first and second spaced end parts defining one dimension of said opening and said rib means defining another dimension of said opening, at least a resilient panel member having a face surface to close the opening, said face surface being longer than the dimension of said opening between said first and second spaced end parts, said internal annular wall surfaces of said first and second vessel-shaped end parts defining spaced annular enclosing wall portions, said face surface of the resilient panel member being adapted to bridge between said internal annular wall surfaces to close said opening into said housing, said rib means having first and second annularly spaced radially extending vertical walls and first and second annularly spaced laterally extending vertical walls, said annularly spaced laterally extending walls of the rib means defining bridging continuations of the annular enclosing wall portions defined by said internal annular wall surfaces of the end parts, said first radial and first lateral vertical walls meeting in acute angular relationship and defining a first panel retaining notch, said second radial and second lateral walls meeting in acute angular relationship and defining a second panel retaining notch, said resilient panel having first and second lateral edges with means thereon complementarily fitting in gas-seal engagement with said first and second panel retaining notches respectively, and with the inner edge of the first and second radially extending vertical walls, said resilient panel being wider than the distance between said first and second

5

panel retaining notches when the panel is in an inoperative position, whereby said first and second lateral edges of the panel will be tightly pressed into engagement with said first and second retaining notches when the panel is in an operative position and lay flush against the internal surfaces around said opening.

BERNARD E. MUSTEE.
